IMPLEMENT FOR INTERWEAVING BRAID

Hope Hanley, P.O. Box 537, Purcellville, Va. 22132

Filed Feb. 13, 1973, Ser. No. 331,737

Term of patent 14 years

Int. Cl. D6—99

U.S. Cl. D3—19 A

FIG. 1

FIG. 2

FIG. 3

FIG. 4

FIG. 1 is a front perspective view of an implement for interweaving braid showing my new design;

FIG. 2 is a rear elevational thereof on a reduced scale, the figure being broken away for convenience of illustration;

FIG. 3 is an end view taken from the top of FIG. 2; and

FIG. 4 is an end view of the bottom end of the design. I claim:

The ornamental design for an implement for interweaving braid, as shown and described.
